UNITED STATES PATENT OFFICE.

HARRY S. VINCENT, OF RIDGEWOOD, NEW JERSEY.

LOCOMOTIVE-BOILER SUPERHEATER.

1,266,184.

Specification of Letters Patent.

Patented May 14, 1918.

Application filed June 12, 1917. Serial No. 174,174.

To all whom it may concern:

Be it known that I, HARRY S. VINCENT, of Ridgewood, in the county of Bergen and State of New Jersey, have invented a certain new and useful Improvement in Locomotive-Boiler Superheaters, of which improvement the following is a specification.

My invention relates, generally, to superheaters of the fire tube type for locomotive boilers, and, particularly, to those of the design of that type, in which the throttle valve is interposed between the superheated steam compartment of the superheater and the cylinders of the locomotive, an early instance of which is exemplified in Letters Patent of France No. 27012, granted to la Compagnie du Nord, under date of December 4, 1860.

The object of my invention is to provide means for conveying superheated steam from a locomotive boiler superheater to the engine cylinders, and controlling the supply, between the superheater and the cylinders, which shall be of simple and inexpensive construction, and be located, except for a limited portion of their extent, entirely exterior to the boiler; and which shall, further, be applicable in connection with superheaters of the present standard type, without substantial change in the construction thereof.

The improvement claimed is hereinafter fully set forth:

In the accompanying drawings: Figure 1 is a side view, in elevation, of the forward portion of a locomotive engine, illustrating an application of my invention; Fig. 2, a front view, in elevation, of the same; Fig. 3, a view, taken similarly to Fig. 1, illustrating a structural modification; Fig. 4, a view, taken similarly to Fig. 2, and partly in section, of the structural modification shown in Fig. 3; Fig. 5, a partial vertical longitudinal section on an enlarged scale, on the line $x-x$ of Fig. 6, and; Fig. 6, a vertical transverse section, on the line $y-y$ of Fig. 5.

My invention is herein exemplified as applied in a locomotive boiler, 4, which is of the usual construction, and is provided, at its forward end with a smoke box, 4^a, which is supported on the ordinary cylinder saddles, 12. A plurality of fire tubes, some of which, 67, are of larger diameter than the others, extends from a firebox at the rear end of the boiler, which is not

shown, to the front flue sheet, 4^d, and the products of combustion pass through the tubes, in the usual manner to the smoke box, 4^a, from which they are discharged into the atmosphere through the stack, 4^b.

In the practice of my invention, referring descriptively to the specific embodiment thereof in connection with a superheater of the standard Schmidt "type A" construction which is herein illustrated, the superheater header, 70, is, as usual, located a short distance forward of the front flue sheet, 4^d, and comprises a rear transversely extending saturated steam compartment, 70^a, which is connected by a short receiving nozzle, 62, with the main steam pipe or dry pipe, 61, and an adjoining forward transversely extending superheated steam compartment, 70^b. Saturated steam entering the compartment, 70^a, from the dry pipe, passes from said compartment through a plurality of return bend pipes, 69, known as "units," which are located in the tubes, 67, in which it is superheated by the products of combustion passing through said tubes, and is delivered therefrom to the superheated steam compartment, 70^b, from which it passes, through two branch steam pipes, 63, to the engine cylinders.

In ordinary practice, control of the admission of steam from the boiler to the saturated steam compartment, is effected by a throttle valve located within the boiler, 90 at the rear end of the dry pipe, and governing the admission of steam from the boiler, through said pipe, to the saturated steam compartment, and the branch steam pipes are disposed inside of the smoke box, 95 each being connected to one of two nozzles at the ends of the superheated steam compartment. In the application of my invention, the superheater header is modified by eliminating the two end branch steam pipe nozzles above stated, and substituting therefor a single central delivery nozzle, which is connected to the casing of a throttle valve located on the outside of the boiler, and controlling the branch steam pipes, instead of the dry pipe, the branch steam pipes, in this case, leading, entirely outside of the boiler, to the engine cylinders. Under this construction, which will now be more fully described, it will be seen that the steam space of the boiler is, at all times, in open communication with the superheater header,

and, then ^{ore}, that the header and superheater units are continuously filled with steam, during the periods that the locomotive is under steam, irrespective of whether the throttle valve be open or closed.

The delivery nozzle, 70^a, of the saturated steam compartment of the header, is connected, by an angle pipe, 5, passing through the top of the smoke box, 4^a, with a forwardly extending nozzle, 6^a, formed on a throttle box or chest 6, which is supported on the outside of, and secured detachably to, the shell of the boiler, 4, immediately in rear of the smoke box, ball joint rings, 6^c, being fitted between the pipe, 5, and the nozzles, 70^a and 6^a, to insure tight joints. The pipe 5, and throttle box, 6, are preferably, as shown, inclosed in a light sheet metal case, 6^b, and the pipe, 5, being supported by the throttle box, and this, in turn, by the boiler, no additional weight is imposed on the superheater header. The branch steam pipes, 63, are connected to opposite sides of the throttle box, 6, and lead therefrom, on the outside of the smoke box, and adjacent thereto, to connections with the distribution valve chests, 12^b, of the locomotive, following, as nearly as may be, the curvature of the smoke box, to a level slightly below the center line of the boiler.

Communication between the interior of the throttle box and the branch steam pipes, 63, is controlled by a throttle valve, 7, which may be of any suitable and preferred construction, and which does not, in and of itself, form part of my present invention. In the instance shown, it is of the single seat balanced top lift puppet type, and is secured to a balancing piston 7^a, fitting a chamber 40 at the bottom of the throttle box, to which steam is admitted, in the usual manner, in the unseating of the valve, by a small pilot valve, 7^b. The throttle box, 6, is closed at top by a removable cap or head, 6^d, in which an operating shaft, 8, is journaled, said shaft passing through a stuffing box, 8^a, on one side of the throttle box, and carrying an inside arm, 8^b, which is coupled to the throttle valve, and an outside arm, 8^c, which is coupled, by a link, 8^d, to one arm of a bell crank lever, 8^e, journaled on the boiler, the other arm of said lever being coupled by a throttle rod, 8^f, to a throttle lever (not shown) in the cab of the locomotive. It will, however, be understood that the specific construction and operating mechanism of the throttle valve, are not essentials of my invention, and that other designs, of which many are known in the art, may be substituted, in the discretion of the constructor.

A circulating pipe, 9, of small diameter is connected to a nozzle on the rear side of the throttle box, opening into the space above the throttle valve, and leads therefrom either to a connection with the steam space, or prefer-

ably to an automatic drifting mechanism, in locomotives on which the latter is applied. By the flow of steam from the saturated steam compartment, through said pipe, a moderate circulation of steam through the 70 superheater units will be effected when the throttle valve is closed.

Figs. 3 and 4 illustrate a structural modification which accords in all essential particulars with the construction above described, is further designed to minimize the obstruction to the view of the engineer occasioned by the outside location of the branch steam pipes, 63. To this end, said pipes, instead of being forwardly and downwardly inclined from the throttle box, as in the instance first described, are first carried forward horizontally therefrom, and are then extended downwardly, projecting into inclined lateral openings, 4^e, in the smoke box, which are preferably located in, or nearly in, line with the transverse central plane of the stack. Said openings are closed, on the inner sides of the branch steam pipes, by cover plates, 4^f, which are secured detachably to the smoke box, to admit of the insertion and removal of boiler tubes adjoining the sides of the boiler.

In addition to the advantages, common to all superheater designs in which the throttle valve is located between the saturated steam compartment and the engine cylinders, i. e., of reducing the liability to destruction of the units through heat applied thereto, by maintaining them constantly filled with steam; the elimination of dampers and their operating mechanism; and the capacity of quicker starting and stopping of the locomotive, my invention reduces to the minimum the obstruction to the smoke box which obtains in the ordinary constructions; supports the throttle box, throttle valve, and connecting pipe, independently of the superheater header, thereby preventing the objectionable imposition of weight thereon, and locates the throttle valve in position where it is readily accessible and is not subjected to the injurious action of a high degree of heat; and necessitates, for its application, only a slight and inexpensive change in the construction of the present standard superheater header.

I claim as my invention and desire to secure by Letters Patent:

1. The combination, with a locomotive boiler, of a superheater header located in the smoke box, and having a single delivery nozzle entirely inclosed therein; a throttle box supported, independently of the superheater header, on the exterior of the boiler shell; an angle pipe secured to, and supported by, the throttle box, said pipe passing through the smoke box and being connected, at its lower end, to the delivery nozzle of the superheater header; branch steam pipes

leading, exterior to the boiler, from the throttle box to connections with the distribution valve chests of the engine; and a throttle valve seating in the throttle box and controlling communication therefrom to the branch steam pipes.

2. The combination, with a locomotive boiler of a superheater header located in the smoke box, and having a single delivery nozzle entirely inclosed therein; a throttle box supported, independently of the superheater header, on the exterior of the boiler shell, and having a forwardly extending delivery nozzle; an angle pipe secured to, and supported by, the delivery nozzle, said pipe passing through the smoke box, and being connected, at its lower end, to the delivery nozzle of the superheater header; ball joint rings interposed between the angle pipe and the throttle box and superheater header; branch steam pipes leading, exterior to the boiler, from the throttle box to connections with the distribution valve chests

of the engine; and a throttle valve seating in the throttle box and controlling communication therefrom to the branch steam pipes.

3. The combination, with a locomotive boiler, of a smoke box having inclined lateral openings; a superheater header located in the smoke box; a throttle box supported independently of the superheater header, on the exterior of the boiler shell; a pipe passing through the smoke box and connecting the superheated steam compartment of the header with the throttle box; branch steam pipes leading from the throttle box to connections with the distribution valve chests of the engine and extending longitudinally in the lateral openings of the smoke box; and cover plates fitted over said openings and secured detachably to the smoke box.

HARRY S. VINCENT.
